WALL MOUNTED HAND DRYER

Jerrell J. Griffin, Los Angeles, Calif.
(18658 Napa St., Northridge, Calif. 91324)

Filed Sept. 8, 1969, Ser. No. 19,062

Term of patent 14 years

Int. Cl. D23—03

U.S. Cl. D23—74

Fig. 1

FIG. 1 is a perspective view of a wall mounted hand dryer showing my new design.

FIG. 2 is a front elevational view thereof on a reduced scale.

FIG. 3 is a side elevational view thereof on a reduced scale.

FIG. 4 is a bottom plan view thereof on a reduced scale.

I claim:

The ornamental design for a wall mounted hand dryer, substantially as shown.
